UNITED STATES PATENT OFFICE.

ADOLPH LANDAU, OF NEW YORK, N. Y.

COMBINED SUSPENDERS AND BELT.

SPECIFICATION forming part of Letters Patent No. 726,441, dated April 28, 1903.

Application filed August 27, 1902, Serial No. 121,156. (No model.)

To all whom it may concern:

Be it known that I, ADOLPH LANDAU, a citizen of the United States, and a resident of New York city, county and State of New York, have 5 invented certain new and useful Improvements in a Combined Suspenders and Belt, of which the following is a specification.

This invention relates to suspenders so constructed that each of the shoulder-straps may 10 be converted into a belt, so that two complete belts may be formed from a single pair of suspenders.

In the accompanying drawings, Figure 1 is 15 a perspective view of the device, showing it arranged as a pair of suspenders. Fig. 2 is a perspective view of a belt formed from one of the shoulder-straps, and Fig. 3 a detail of the back connection.

The letters *a a* represent the shoulder- 20 straps of a pair of suspenders, each connected at its rear end by a ring *b* to a rear tab *c*. The tabs *c* are provided with a lower button-hole *c'* and with a number of perforations *c*² above said buttonhole. At the front the 25 shoulder-straps *a* are doubled around a buckle *d* and are made adjustable in length by a slide *e*.

The front tabs *f* depend from a strap *f'*, having perforations *f*², adapted to be engaged 30 by the tongue of buckle *d*, so that in this way the tabs *f* are removably secured to the shoulder-straps *a*. A keeper *a'* above buckle *d* confines the free end of strap *f'*.

At the back the straps *a* are connected with 35 each other by a transverse band or hinged clasp *g*, which is removably secured at each end to one of the straps. The attachment between clasp and straps is preferably effected by means of spring-hooks *g'* at the 40 ends of clasp *g*, which are adapted to be brought into engagement with the rings *b*. When the straps *a* are connected with each other by the clasp *g* and the front tabs *f* are buckled to said straps, the device constitutes

a pair of suspenders, Fig. 1. To convert the 45 suspenders into a pair of belts, the clasp *g* is uncoupled from each of the shoulder-straps, so as to disconnect the same, and the front tabs are unbuckled. Each shoulder-strap will thus be transformed into a belt, the buckle *d* of which may be made to engage either one of the eyes *c*² of rear tab *c*, while the free end of the tab is confined by a keeper *a'*, Fig. 2.

What I claim is—

1. Combined suspenders and belt composed 55 of a pair of connected shoulder-straps, a pair of rear tabs, means for removably connecting the straps with each other, front tabs having straps, and buckles adapted to engage said 60 straps and the rear tabs, the shoulder-straps when disconnected being adapted to form two belts, substantially as specified.

2. Combined suspenders and belt composed 65 of a pair of connected shoulder-straps, a pair of rear tabs having a series of perforations, means for removably connecting the straps, front tabs having straps, and buckles adapted to engage said straps and the rear tabs, the shoulder-straps when disconnected being 70 adapted to form two belts, substantially as specified.

3. Combined suspenders and belt composed 75 of a pair of shoulder-straps, a pair of rear tabs, a pair of connecting-rings, a clasp having a pair of end catches adapted to removably engage said rings, front tabs having straps, and buckles adapted to engage said 80 straps and the rear tabs, the shoulder-straps when disconnected being adapted to form two belts, substantially as specified.

Signed by me at New York city, New York, this 26th day of August, 1902.

ADOLPH LANDAU.
